JACKING APPARATUS

John Gutmann, Jr., St. Albans, N. Y., and Austin M. Wolf, Newark, N. J., assignors to Motor Jack Corporation, New York, N. Y., a corporation of New York

Application August 28, 1930, Serial No. 478,384

13 Claims. (Cl. 254—86)

This invention relates to jacking apparatus for motor vehicles, and is an improvement over jacking apparatus disclosed in our application for patent bearing Serial Number 469,015, filed Jan. 5, 1931.

An object of the present invention is to provide a motor vehicle with a jack unit mounted centrally on each axle of the vehicle, a power take-off on the transmission, and driving mechanism therebetween, the system being built into the motor vehicle and whereby the power required to operate the jacks is derived from the engine of the car.

Further objects of the invention reside in the provision of gears in jack operating mechanism by which power take-off is effected directly from the present transmission gears, the system being so adapted that it may be incorporated as standard equipment in association with the transmission mechanism; in novel and inexpensive control means operated from the dash for selective operation of either jack for upward or downward movement thereof; in means to control proper shifting of the control means in the proper position; in improved means for rendering inoperative the power take-off mechanism when the jack has reached its limit of movement in either direction; in means to prevent the operation of the jack from being continued in the direction in which it was last moved; in means for normally supporting each jack in horizontal, elevated position when inoperative; in means which become automatically operable upon the starting of the jack operating mechanism to swing the jack down into vertical operating position and automatically operable to swing the jack back into normal horizontal inoperative position at the limit of the retracted stroke of the jack.

The invention has for a further object the provision of a device of the class mentioned which is of simple, durable construction, dependable in use and efficient in action.

These and other objects, which will become more apparent as the description progresses are obtained by the novel construction and combination of parts hereinafter described and shown in the accompanying drawings, forming a material part of this disclosure and in which:

50 Figure 1 is a side elevation of a motor vehicle chassis with the invention shown in full lines.

Figure 2 is a section taken on line 2—2 of Figure 1.

Figure 3 is a section taken on line 3—3 of Figure 1.

Figure 4 is a modified form of rear jack mounting.

Figure 5 is a plan section showing power take-off as applied to the transmission of motor vehicle.

Figure 6 is a sectional view taken substantially along the line 6—6 of Figure 5.

Figure 7 is a sectional view taken on a line 7—7 of Figure 6.

Figure 8 is a sectional view taken on a line 8—8 of Figure 7.

Figure 9 is a similar view taken on a line 9—9 of Figure 7 through the spring detent pin.

Figure 10 is a sectional view taken on a line 10—10 of Figure 8.

Figure 11 is a detail indicating the positioning notches for the shift shaft.

Figure 12 are views showing the selector and shifter handle used in the invention.

Figure 13 is a sectional view through the power take-off sleeve, showing the ends of the selective jack drive shafts.

Figure 14 is a vertical sectional view of a jack as applied to the front axle of a motor vehicle and shown in a horizontal and out-of-use position.

Figure 15 is a sectional view taken on a line 15—15 of Figure 14.

Figure 16 is a vertical sectional view of the jack shown in Figure 14 in a vertical and ready-to-use position. The broken lines indicating the inactive position of the jack foot.

Figure 17 is a detail of the spring-pressed latch for the jack foot.

Figure 18 is a sectional view taken on a line 18—18 of Figure 14.

Figure 19 is a front view of the jack swivel limiting means.

Figure 20 indicates various positions of the automatic throw-out finger.

The description of an embodiment of the invention follows. Starting with the power take-off 20 and referring to Figure 5, a conventional three speed and reverse transmission is shown.

The only difference lies in the aperture in, and the machined face on, the side of the case adjacent to the first speed and reverse gears respectively, 18 and 27, of the countershaft. The plane passing through the main and counter-shafts is shown horizontal, in conformity with the present trend and because it favors the ensemble. Two stamped gears, 28 and 29, with a spacer 30 between them, are secured to the tube 31.

Figure 21 is a side elevation of a motor vehicle chassis with the invention shown in full lines.

Figure 22 is a section taken on line 2—2 of Figure 21.

Figure 23 is a section taken on line 3—3 of Figure 21.

A single gear could be used here but the two 55

stampings actually replace it, at a saving of cost and weight. Supported within the tube 31 by bushings 26, is the front shaft 32 connected with the flexible shaft 33 and the rear shaft 34, to the 5 end of which is secured the universal joint yoke 35. While either flexible or rigid shafts can be used, it is desirable to use the flexible shaft at the forward end in order that it may be readily guided around obstructions (such as the bell- 10 housing) and a rigid shaft be used in the rear where there are no space restrictions. A collar 36 is secured to shaft 32, abutting tube 31 on one side and the retainer 37 on the other and within which it freely turns. A similar collar 38 and 15 retainer 39 affixes shaft 34 to tube 31, with rotational freedom. In this manner, any axial shifting of gears 28-29 and tube 31 is accompanied by shafts 32 and 34. A collar 40, also welded to tube 31, provides space between itself 20 and gear 29 for a shifting fork. If the gears 28-29 are shifted to the left, gear 28 engages the first speed gear 18. If the shift is made to the right, the reverse idler 27 is engaged and the tube 31 rotates in the opposite direction. The arrows 25 in Figure 6 indicate the rotation of the various gears under the latter condition. Looking toward the front of the car from behind the transmission, the tube 31 rotates in a clock-wise direction.

30 A grooved collar 41 is slidably mounted on tube 31 and has a pin 42 secured to it and reposing in the slots 24 of the tube. Shifting collar 41 to the left or right causes pin 42 to engage the notched end 43 of either shaft 32 or 34 and thereby conveys the drive from gears 28-29 to either shaft. The mechanism just described is a selecting clutch.

35 The manual control for the power take-off mechanism is shown in Figure 7. A handle 44 on the instrument board (see Figures 1 and 12) actuates the control shaft 45 through the intermediary of the flexible shaft 46. The latter is housed within a protecting and guiding casing 47. Pushing handle 44 toward the board shifts 40 shaft 45 to the right of Fig. 7. At the same time shifting fork 48 is similarly actuated. In this event, gear 29 engages the reverse idler 27. This gearing is used for jacking up the car because of the resultant greater reduction as compared 45 with gear 28 meshing with the first speed gear. The latter gearing is used for letting the car down which, of course, requires less effort than raising. The operator first decides whether the car is to be jacked up or lowered, and he then 50 pushes or pulls handle 44 accordingly. After thus selecting the proper gear drive, he decides which of the two jacks is to be operated. Swinging the handle to the right or left, effects this choice. Proper co-ordination of the various 55 movements is prescribed by an H slot to be described later.

60 A plate 49 on the instrument below the handle 44 indicates the proper direction of rotation for the selection of either jack. Rotating handle 44 to the right (as viewed by operator from the seat), causes counter clockwise rotation of shaft 45, viewed from the left or front end. Pin 21, secured to shaft 45 and riding in a helical slot 50, formed in the hub 51 of shifting fork 56, shifts 65 the latter to the left, thus picking up the front shaft 32 and imparting rotation thereto from tube 31. Clock-wise rotation shifts fork 56 to the right, causing clutching of the rear shaft 34. 70 As the hub 53 of fork 48 is rotationally free on 75

shaft 45, it does not move when fork 56 is shifted.

A collar 54 is fixed to shaft 45 at each side of the hub of fork 48. Movement of collars 54 requires only axial movement of shaft 45, while rotation of the latter is required to move fork 56.

The H slot mechanism controlling proper shifting, is shown in Figures 9, 10 and 11. A thimble 57 is slidably mounted in a hole in shaft 45. Within it is a slidable detent pin 58, a spring 59 10 between the two tending to spread them apart. In this way the thimble 57 bears against the circular insert 60, dropping into notches 61 in the latter in the "neutral", "down" and "up" positions. Pin 58 bears against the sleeve 62 which 15 holds insert 60. The two ends of the insert are brought together, with a slot forming the cross slot of the H corresponding to the space formed when mounted in the sleeve. Within the cross slot of the H rides detent pin 58, from the neutral 20 position to either of the gear engagement positions. Rotary motion of shaft 45 is thereby prevented till the pin 58 reaches either end of the slot. Now after either gear 28 or 29 has meshed with the first speed or reverse idler gears 18, 27, 25 respectively, rotary motion can be imparted to shaft 45, thereby "picking up" either the front or rear jacks. As shown in Figure 9, notches 61 at either extreme of the shaft rotation allow thimble 57 to drop in to prevent collar 41 from shifting. 30

As will be explained further on, either jack automatically throws the gears of the power take-off into neutral when at either end of the jack's stroke. The movement is imparted by the jacks to either drive shaft and in turn either shaft 32 35 or 34. The collars 36 and 38 cause axial shifting of the tube 31 in like direction. Assuming the pin 58 to be in one of the extreme ends of the transverse portions of the H slot, it would resist axial shifting of control shaft 45, unless some part 40 fractured.

To prevent any such accident, a bevel 63 is located at each corner of the H, thereby allowing pin 58 to over-ride insert 60. The automatic throw-out leaves thimble 57 engaging the central notch which is continuous as shown dotted in Figure 11, as compared with three individual notches at either end of insert 60. The automatic throw-out causes pin 58 to ride up the bevel 63 and slide parallel to the central portion of the 50 H-slot upon the inner surface of insert 60 to a position intermediate the two transverse portions of the H-slot. The operator has only to turn handle 44 which is now in its neutral in-and-out position. 55

Referring to Figures 1, 2 and 3 the flexible shaft 33 within the casing 64 conveys the drive from the power take-off to the front jack unit 65, mounted on the front axle 66. Due to the jack assuming the position shown in the dotted lines, shaft 33 is offset toward the left, making a more favorable position for it. The rear jack 69 derives its power from shaft 34, through the universally jointed shaft 67 and finally shaft 68. Jack 69 is mounted in a boss 70 formed on the pinion shaft housing 65 71 of rear axle 72. If so desired, it can be placed to the rear of the axle as shown in Figure 4, support being a boss 73, forming part of rear cover plate 74. The jack center head does not necessarily coincide with the center of the axle, as 70 when one end is up stability is obtained from the contact of the other axle's wheels with the ground, making a three-point support. In the event that it is desirable to be able to jack-up both ends, the feet 75 of the jacks are enlarged 75

and the jacks can be brought quite close to center by suitable design to accommodate them in this position.

The method of jack operation will be explained with particular reference to the front axle application, as the rear jack functions in like manner. In Figure 14, which is a vertical section through the driving shaft, with the jack out of action, it will be seen that the unit is supported in a boss 76 forged integrally with the front axle bed 66. The flexible drive shaft 33, from the power take-off, terminates in shaft 78. At the left end of same two external splines 79 mate with corresponding internal splines 80 inside worm 83. The different positions assumed by shaft 78 are: the one shown ("neutral" for the power take-off gears) and the two indicated by the dotted lines 81 and 82. Shaft 78 is therefore in continual driving connection with worm 83, regardless of its position. The worm rides directly within a bored hole in the housing 65, the outside of the teeth forming the journal of the bearing thus made. Worm-wheel 84 driven by worm 83, has an internal thread which receives the threaded rod 85. In Figure 16, the thread extends from line T to the top of rod 85. A base 75 is secured to its bottom. Figure 16 shows the jack in a vertical position ready to operate.

To swing the jack from its normally horizontal position to a vertical operating position, a washer 86 is secured to the upper end of the threaded rod 85. For a limited distance at the beginning of its travel (and similarly at the end of its travel when retracting), the washer 86 travels within the nest of flat springs 87, secured at the upper end of a protecting tube 88. The added resistance thus encountered causes a drag and the jack-unit revolves momentarily with drive shaft 33, whose rotation is clock-wise (looking toward the front).

The extension 89 of the housing 65 swivels in the front axle boss and is machined with a tongue 90 that fits into a corresponding groove in washer 91. The latter has a rearwardly extending boss 92 which rides in a milled slot in the axle boss. The shape of boss 92 permits an easy machining operation for the slot. Figure 19 indicates same, viewed from the front, and shows the 90° limit of travel for the jack unit. If one were to disregard the I-beam shown in Figure 14, this view would be a horizontal section of the jack through the worm axis, with the jack in the vertical position.

The extension 93, may be made a continuation of worm 83, to provide manual operation of the jack if desired, in the event of engine failure. The end 93 can be formed to fit the rim or wheel wrench brace, or other convenient tool.

The threaded rod 85 has a keyway 94 extending down to the bottom of a key-block 95 (see Figure 16). At either end of the jack travel, the end of the keyway 94 moves the key-block 95, which in turn causes the automatic throw-out. The key portion 95' of block 95 also prevents rotation of rod 85, restricting its movement to up and down. As seen in Figure 15, the block portion 95' is guided in a slot 96 in the casing 65 and is provided with an elongated hole 96'. Into the latter extends a pin 97 integral with a bell-crank consisting of arms 98 and 99. The latter, through the intermediary of link 100, shifts the sliding member 101 on rod 102. The arm 103 rigid with sliding member 101 extends toward, and surrounds half of shaft 78. This bearing on shaft 78 is merely to keep member 101 in line. A finger 104, pivoted to arm 103, is normally in

the position shown by the dotted lines in Fig. 14, a spring 105 holding it thus. Let us consider for the moment that the finger 104 is fixed in the dotted line position and pivoted to arm 103.

The jack is up. To drop the jack and raise the car, gear 29 is meshed with the reverse idler. In this rearward shift of tube 31, shafts 33 and 68 are also carried rearwardly, and with them shaft 78 and the corresponding shaft of the rear jack. The splined connections permit this movement; at the same time a collar 106, secured to shaft 78, travels rearwardly or to the right of Fig. 14. A bronze washer 107 is located at each side of collar 106 and a light shell 108 is spun over the assembly. A thrust bearing, for thrust in either direction, is thus provided. The assembly 106 now lies adjacent to the arm 103. Shaft 32 is now picked up by pin 42 and power conveyed to the front jack by means of shaft 33 which rotates in a clock-wise direction. Worm 83 is right-handed, resulting in counter clock-wise rotation of worm wheel 84. The thread on rod 85 is right-hand and the rod therefore descends. If the jack is left to run to its limit, the latter is reached when the upper end of keyway 94 on rod 85 carries the key block 95 down from the position shown in Figure 15 to its lower position. In so doing, the sliding member 101 is moved to the left of Fig. 14 and arm 103 carries the collar assembly 106, and with it shaft 78, to their mid or neutral positions. The gears in the power take-off have also been thrown out of mesh, to their neutral position, due to the pull of shaft 33. One cannot attempt to continue to drop the jack as arm 103 blocks the shaft 78 and the power take-off sliding assembly. One can move same forward or to the left and engage first speed gear, which imparts the opposite rotation to shaft 33 and the jack is raised or the car lowered. The collar assembly 106 is now to the left against the end of finger 104.

When the block 95 is raised, neutral position is again attained. This sequence is diagrammatically indicated in Figure 20 with reference to the vertical line x-x wherein "a" indicates the positions of finger 104, block 103 and collar 106, when the jack is up and power take-off in neutral; "b" the positions of the said respective elements when the mechanism is set to lower the jack; "c" the positions of the said respective elements when the automatic throw-out is actuated to bring the power take-off back to neutral; "d" the positions of the said respective elements when the mechanism is set to raise the jack; and "e" the positions of the said respective elements when the automatic throw-out is actuated to bring the power take-off back to neutral. The arrows show the direction in which the indicated elements are moved.

In so far as one jack is concerned, a rigid member 103-104 would suffice but as both jacks, front and rear, have sliding members, one would block the outer under certain conditions. Therefore finger 104 is hinged as previously described. When the jack is raised to its extreme position, the final rearward movement of member 101 causes the small arm 109 which is rigid with arm 104 to come into contact with the washer 110, thereby raising the finger 104 to the position shown in full, in Figure 14. In order to effect the shifting of the control mechanism to neutral during the final upward movement of the jack, the spring 111 maintains block 95 in its lowest position until the bottom of slot 94 contacts with and raises it. Either jack can then be operated

without interference of one control with the other.

Assuming the parts to be in the relative positions shown in Figure 14, the operator might 5 lower the jack only part way and then raise it again, thereby avoiding the automatic throw-out. Collar assembly 106 is originally moved to the right to lower the jack. The operator then returns it to the neutral position shown and 10 passes on to the left in order to raise the jack. In so doing, assembly 106 would escape from finger 104. At the beginning of the jack travel in its descending direction, block 95 also moves with it. The initial slight movement of member 15 101 allows finger 104 to drop into place and prevent any escapement.

When the jack is raised, the additional resistance at the end of the stroke offered by the springs 87 when washer 86 enters between them, 20 causes the jack assembly to swivel in its mounting and follow the counter clock-wise rotation of shaft 33. The foot 75 is now in close proximity to a spring pressed latch 112 which is nested in boss 113 forged in the axle bed (see Figure 17). 25 A slight further movement of the mechanism before the automatic throw-out occurs brings the jack foot 75 toward the left (see right portion of Figure 16). In this way the jack is caught and held in the horizontal position.

30 When the jack is lowered, the foot 75 first moves horizontally to the right of Fig. 16, rides over the latch 112 and the jack unit swings into a vertical position. To prevent rattling, a taper 35 114 is provided on the latch (see Figure 17), its spring 115 providing an automatic take-up, thus furnishing a wedging action between latch 112 and foot 75. The springs 87 also provide an anti-rattle means. In the event that the jack should hesitate to swing to its horizontal position, due to any outside resistance or restriction 40 such as late relief of weight from the jack-foot, the latch 112 will catch it as it swings by.

The throw of either jack will not interfere with 45 brake rods, hydraulic brake lines, etc. provided the latter are suitably located so as not to lie in the path of the jack.

There is sufficient room to allow plenty of latitude in this regard.

To prevent the operator making a false manipulation, in spite of instructions and the markings 50 on the instrument board, an interlocking mechanism may be provided.

When the jack is up, the operator might attempt to raise it again. This would be possible 55 because the raised finger 104 (Figure 14) would not block the operator from getting into mesh with the first speed gear and then "picking-up" either jack. A parallel contingency is impossible when the jack is all the way down as the automatic throw-out would only allow the selection of the first speed countershaft gear, which is the logical one to next use, and the operator is blocked by arm 103 in attempting to again mesh the reverse idler.

60 Referring to Figures 7, 8, 9 and 10, the keys 119 and 120 are separated by the spacer 121. The latter has the strips 122 secured to it which holds the keys in place, against the filler ring 65 60. A semi-circular spacer 123 completes the circumference. A spring 124 also holds the keys in place and adds friction which retains them in whatever position they might be shifted. Referring to Figure 10, the neutral position of pin 75 70 58 is shown. The regular shifting to raise the

jack, is from neutral to A and then to B. A slot 126 in the key 120 allows motion of pin 58 from A to B. Suppose the automatic throw-out took pin 58 from position B parallel to the central portion of H-slot, as previously explained. The key 120 is shifted by pin 58 to the right as shown by the dotted lines of Fig. 10. Turning the handle 44 on the dash, pin 58 walks out of the key slot 126 to normal neutral. If the previous shift that is, the shift to raise the jack were attempted, 10 the key 120 would block pin 58 at A and no "pick-up" could be enacted. However, when the next action is made, to lower the jack, pin 58 in shifting from C to D throws the key 120 back to its former position wherein its slot 126 registers with the extreme end of the right-hand (Fig. 10) transverse position of the H-slot and a subsequent A—B shift is possible. The sliding action of the key is obtained due to the rounded corner thereof. 20

As changes of construction could be made within the scope of the invention, it is intended that all matter contained in the foregoing description or shown in the accompanying drawings shall be interpreted as illustrative and not in 25 a limiting sense.

While we have shown and described a preferred form of embodiment of this invention we are well aware that other modifications may be made and we therefore desire a broad interpretation of 30 the invention within the scope and spirit of the disclosure herein and the claims appended hereto.

Having thus described our invention, what we claim as new and desire to secure by Letters Patent, is:— 35

1. In combination with the transmission of a motor vehicle, having a forward gear and a reverse gear, a power take-off for jacking apparatus, adapted for operative engagement with the forward gear and the reverse gear, selectively. 40

2. In combination with a motor vehicle transmission having a gear on the countershaft and a reverse idler, a power take-off for jacking apparatus adapted for selective operative engagement with the gear and the idler. 45

3. In combination with the first speed gear and reverse gear of the transmission of a motor vehicle, a power take-off for jacking apparatus adapted for selective operative engagement with the said speed and reverse gears. 50

4. In combination with a motor vehicle transmission having a gear on the countershaft and a reverse idler, a power take-off for jacking apparatus; said power take-off having a shaft, and rotative means on the shaft adapted for selective operative engagement with the gear and the reverse idler, by which the shaft may be driven in either direction. 55

5. In a jacking apparatus, the combination with a control shaft movable longitudinally and rotatably and two jack shafts arranged in axial alignment, and a shiftable means associated with the control shaft and jack shafts; means to move the jack shafts longitudinally in either direction depending upon the longitudinal movement of the control shaft and to move the shiftable means in either direction depending upon the direction of rotation of the control shaft. 60

6. In a jacking apparatus, the combination with a control shaft movable longitudinally and rotatably and two jack shafts arranged in axial alignment, and a shiftable means associated with the control shaft and jack shafts; means to move the jack shafts longitudinally in either direc- 70 75

tion depending upon the longitudinal movement of the control shaft and to move the shiftable means in either direction depending upon the direction of rotation of the control shaft, and 5 means for preventing rotative movement of the control shaft until it has first been moved longitudinally.

7. The combination with a lifting jack and driving means therefor, of a shaft, means for 10 communicating rotative movement from the driving means to the shaft, said shaft being slidable with relation to the driving means and jack, and means becoming operative when the jack has reached the limit of its stroke in either direction 15 to slide the shaft, to move the communicating means out of engagement with the driving means.

8. Jacking apparatus for a motor vehicle comprising a lifting jack in swinging engagement 20 with the vehicle, a power take-off directly associated with the transmission of the vehicle, means for communicating power to the jack from the power take-off, means for normally supporting the jack in horizontal, elevated position, and 25 means becoming automatically operable upon the starting of the first mentioned means to swing the jack down into vertical operating position and operable to swing the jack automatically back into normal horizontal position upon reaching the 30 limit of its retracted movement, and means to automatically cause cessation of power to the jack when the jack reaches the limit of its retraction.

9. In combination with a swingable lifting jack for a motor vehicle normally in substantially 35 horizontal position thereunder and adapted for operation from the transmission of the vehicle, means becoming automatically operative upon the application of power to extend the jack, to swing the jack down into substantially vertical operating position, said means becoming operable upon the jack reaching the limit of its retraction to swing the jack back to its initial position, and means to automatically cause cessation of power to the jack when the jack reaches the 40 limit of its retraction.

10. In combination with a swingable lifting jack for a motor vehicle normally in inoperative position thereunder and adapted for operation from the transmission of the vehicle, means be- 45

coming automatically operative upon the application of power to extend the jack, to swing the jack down into substantially vertical operating position, said means becoming operative upon the jack reaching the limit of its retraction to swing the jack back to its initial position, and means to hold the jack in the latter position, and means to automatically cause cessation of power to the jack when the jack reaches the limit of its retraction. 5

11. In combination with a swingable lifting jack for a motor vehicle normally in inoperative position thereunder and adapted for operation from the transmission of the vehicle, means becoming automatically operative upon the application of power to extend the jack, to swing the jack down into substantially vertical operating position, said means becoming operative upon the jack reaching the limit of its retraction to swing the jack back to its initial position, means to hold the jack in the latter position, and means to automatically cause cessation of power to the jack when the jack reaches the limit of its retraction. 10 15

12. Jacking apparatus for a motor vehicle comprising a lifting jack in swinging engagement with the vehicle, a power take-off associated with the transmission of the vehicle to operate the jack, means for communicating power to the jack from the power take-off during the lifting range 20 of the jack, automatic means to swing the jack into operating position upon the application of power to the jack, and means to automatically cause cessation of power to the jack when the jack reaches the limit of its extension. 25 30 35

13. Jacking apparatus for a motor vehicle comprising a jack in swinging engagement with the vehicle, means communicating power from the motor of the vehicle to the jack to operate the same, means to swing the jack from inoperative 40 position to operating position upon application of power to the jack and to swing the jack back to inoperative position upon the jack reaching the limit of its retraction, and automatic means for cutting off the power from the jack when the same has reached the limit of its retraction. 45

JOHN GUTMANN, JR.
AUSTIN M. WOLF.
